UNITED STATES PATENT OFFICE.

CHARLES C. MADISON, OF SCANDIA, KANSAS.

PARTITION FOR STOCK-CARS.

1,189,151.

Specification of Letters Patent. Patented June 27, 1916.

Application filed November 23, 1915. Serial No. 63,016.

To all whom it may concern:

Be it known that I, CHARLES C. MADISON, a citizen of the United States, residing at Scandia, in the county of Republic and State of Kansas, have invented new and useful Improvements in Partitions for Stock-Cars, of which the following is a specification.

This invention relates to stock cars and more particularly to a movable partition for the same. It frequently happens that shippers of stock have occasion to send what is known as mixed shipments of cattle, sheep, hogs and the like, and as the proportions of such shipments vary it is difficult with means at present available to properly separate the same.

The present invention has for its object to produce a simple and improved movable partition which may be readily adjusted and secured in various positions as may be required.

A further object of the invention is to simplify and improve the construction of the said movable partition and the manner of mounting or supporting the same.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings,—Figure 1 is a sectional view taken transversely through the body of a stock car to which the improvement has been applied. Fig. 2 is a detail sectional view taken on the line 2—2 in Fig. 1. Fig. 3 is a sectional detail view taken on the line 3—3 in Fig. 1, looking down on one end of the movable partition. Fig. 4 is a perspective detail view showing one of the metallic cleats or carriers whereby the ends of the partition are supported. Fig. 5 is a perspective view showing the opposite side of the said cleat or carrier with the roller and bolt carrying bracket attached. Fig. 6 is a perspective detail view showing the roller

and bolt carrying bracket detached from the cleat. Fig. 7 is a sectional detail view enlarged taken on the line 7—7 in Fig. 1. Fig. 8 is a sectional detail view taken on the line 8—8 in Fig. 7.

Corresponding parts in the several figures are denoted by like characters of reference.

The car body A, which is of the customary construction, is provided with the interior studding 15 on which longitudinal boards or planks 16 are secured, said planks being arranged in upper and lower pairs, the lower pair being near the floor of the car and the upper pair being at a suitable elevation to support a partition at a desired height. The planks of each pair are spaced apart, and on the respective planks are secured the track bars 17 which are likewise spaced apart for the admission of supporting wheels or rollers 18 which are of the customary construction employed in supporting rollers for doors and the like, said rollers being annularly grooved to produce flanges adjacent to the opposite faces thereof.

The partition B consists of a panel which may be of solid construction, or it may be made up of spaced bars 19, as shown in the drawing, said bars being reinforced by a diagonal bar 20. The panel or partition is supported at the ends thereof by means of carriers C, each of said carriers consisting of a metallic cleat of U-shaped cross section having at the lower end thereof a supporting flange 21, the ends of the panel being inserted between the side members 22 of the cleat or carrier, being supported at its lower end on the flange 21. A bolt 23 extending transversely through the side members 22 near the upper ends thereof will prevent upward displacement of the panel relatively to the cleat or carrier.

Bolted or otherwise secured exteriorly on the end walls 24 of the cleats C near the upper and lower ends thereof are brackets 25, each bracket having a laterally extending arm 26, and each bracket being also provided on the side thereof with a loop or eye 27. The supporting wheels 18 are mounted for rotation on the brackets 25 and on the laterally extending arms 26 of said brackets, each bracket being provided with two wheels or rollers 18 which are disposed in an approximately horizontal plane. The brackets 25 are properly spaced on the cleats C so that the rollers

will engage between the track bars 17 of the upper and lower tracks, and it is obvious that owing to the use of a plurality of rollers rocking motion of the cleats as well as the partition B carried thereby will be prevented.

Each cleat C is provided on one of its side faces with keepers 28 which are arranged in axial alinement with the eyes 27, 10 said keepers and eyes serving to support bolts 29 that are actuated by springs 30 so as to engage recesses or apertures 31 which are formed in some of the track rails or bars 17. Each bolt 29 is provided with 15 a laterally extending stud 32 which by turning the bolt about its axis may be brought into registry with a notch 33 formed in the bracket 25, thus permitting the bolt, when retracted against the tension 20 of the spring 30, to be locked or secured by a slight turn about its axis.

It will be readily understood that by the use of the cleats or supporting members C partition members or panels B of various 25 heights may be employed. It is also evident that as many partition members as may be desired may be used in a single car by providing the requisite number of cleats. When the partition members are not required for 30 present use they may be stored, and the cleats or supporting members C may be moved to one end of the car where they will occupy but little space, or they may be detached from the tracks, if desired and re- 35 moved from the car. By retracting the bolts of the cleats supporting one of the panels, such panel may be moved lengthwise of the car to a desired position where it may be firmly secured by again releasing 40 the bolts and permitting them to engage

some of the perforations 31 at the desired point.

Having thus described the invention, what is claimed as new, is:—

1. A stock car having upper and lower 45 tracks extending longitudinally along the inner faces of opposite side walls thereof, L-shaped brackets having horizontal arms provided with flanged rollers engaging the tracks, U-shaped supporting cleats secured 50 on and carried by the vertical arms of the L-shaped brackets traveling along the upper and lower tracks, and a partition panel terminally engaging and supported by the cleats at the two sides of the car; the cleats 55 and the vertical arms of the L-shaped brackets being provided with alining keepers and eyes, respectively; and spring actuated bolts guided in said eyes and keepers and adapted for engagement with the track members to 60 secure the parts in adjusted position.

2. A stock car having upper and lower tracks extending longitudinally along the inner faces of opposite side walls thereof, 65 U-shaped supporting cleats, each cleat having brackets provided with anti-friction rollers engaging the tracks, and each bracket having a laterally extending eye, keepers on the side walls of the respective cleats, 70 said keepers being in axial alinement with the eyes of the brackets, and spring actuated bolts mounted in the eyes and keepers, some of the track members being provided with apertures to be engaged by said bolts.

In testimony whereof I affix my signature 75 in presence of two witnesses.

CHARLES C. MADISON.
